UNITED STATES PATENT OFFICE.

ALBERT G. CHARTERS AND JOHN GRIFFITH JONES, OF WATFORD, ENGLAND.

ELECTRICAL FUSE.

No. 889,200.

Specification of Letters Patent.

Patented June 2, 1908.

Application filed June 21, 1907. Serial No. 380,104.

To all whom it may concern:

Be it known that we, ALBERT GEORGE CHARTERS and JOHN GRIFFITH JONES, subjects of the King of Great Britain and Ireland, residing at Cardiff Road, Watford, in the county of Hertfordshire, England, and at Garthroyd, Lower Whippendell Road, Watford, in the county of Hertfordshire, England, have invented certain new and useful Improvements in Electrical Fuses, of which the following is a specification.

This invention relates to an improved electrical fuse which automatically remakes the circuit on a wire fusing and can be repaired without interfering with the circuit.

The fuse is provided with several fuse wires mounted on a revolving insulator between spring tension devices serving to make contact with the terminals. The insulator is controlled by a spring and on a wire fusing the contacts are withdrawn by their springs from the terminals and the insulating body turns to bring the next pair of contacts carrying another wire into contact with the terminals so that the circuit is instantly remade. Successive wires are brought into the circuit in the same manner and the fuse can at any time be repaired without breaking the circuit.

In order that our invention may be more readily understood, reference is had to the accompanying sheet of the drawings in which:

Figure 1 is a vertical section of an automatic fuse according to our invention; Fig. 2 is a plan; and Figs. 3 and 4 are detail views.

A is the insulating body of the fuse, usually of porcelain, and it is mounted free to turn in the brackets B and B¹ from which it can readily be removed. The lower end rests in a recess b in the bottom bracket while the upper reduced end a turns in the end of a slot b¹ in the top bracket and is held in the slot by a plate C pivoted at c and secured by a set screw c¹. The bottom bracket B¹ is slotted obliquely at b², and through this slot is passed the plate d holding the end of the spring D to which it is attached by the small pin d¹. This spring is placed in the recess a¹ of the insulator A and is secured to the insulator at its upper end. The plate d bears against the stops b³ on the bracket B¹ and serves to put the spring D in tension. The spring is wound up by pulling down the plate d and turning it as far as required. On release the plate is held by the stops b³ and

the spring therefore tends to turn the insulator. If the fuse wires are not inserted the insulator can be turned directly for winding purposes and while the fuse wires are being inserted the insulator is held from turning by the stop b⁴ in the bottom bracket. The fuse can be readily removed from the brackets by turning the plate d so that it passes through the slot b² when the top of the insulator, after the plate is turned back, can be withdrawn from the slot in the upper bracket.

The insulator is provided in the arrangement shown with four arms E at both top and bottom and these arms are recessed at e to receive the contact and tension devices consisting of a stem F (of triangular or square form in section), the disk f and the contact head f¹. On this stem is the spring G which when released draws the stem F into the recess as shown at the left hand side of Fig. 1. The fuse wire H is attached to the top and bottom contact heads f¹ by the screws f² the heads being drawn towards each other for attachment, so that the wire holds them in place ready to make contact with the spring terminals J in the manner shown in Fig. 4, where one of the contact pieces f¹ is just about to enter between the two arms of the terminal.

The action of the apparatus is as follows: On the destruction of a fuse wire H the tension and contact devices are released and the springs G draw the corresponding contact heads f¹ out of the terminals. The insulating support is thus released and turns under the force of the spring D until the next contacts, already united by a fuse wire, are brought into the terminals, when the circuit is again completed. This movement is repeated at each fusing of the wire until the fuse wires are exhausted, but these may of course be replaced while the fuse is in use so that interruption of the circuit is unnecessary.

As applied to fuses of the oil break type the general arrangement is the same but the fuse is placed horizontally in the oil bath and the details are arranged accordingly.

What we claim as our invention and desire to secure by Letters Patent is:

1. In an automatically replaceable fuse, the combination of a rotating insulator, a support, a controlling spring for the insulator, spring controlled contact pieces at each end of the insulator, fuse wires uniting the contact pieces and terminals receiving

the contact pieces, which when a wire breaks are withdrawn automatically from the terminals to permit the insulator to turn.

2. In an automatically replaceable fuse, 5 a spring controlled rotating insulator, recessed arms at both ends of the said insulator, contact pieces mounted in the said arms, springs in the recesses tending to withdraw the said contact pieces and fuse wires 10 connecting the contact pieces and drawing them out against the force of the springs.

3. In an electrical fuse, a rotating insulator, brackets receiving the ends of the said insulator, a spring mounted within the insulator and attached to it a slot in one bracket, 15 a bar connected to the end of the spring and adapted to pass through the slot, stops on the bracket to retain the bar and spring controlled contacts on the insulator united by 20 fuse wires, substantially as herein described.

4. In an electrical fuse, the combination of

a rotating insulator A, brackets B and B¹ supporting it, a slot b¹ in one bracket receiving one end of the insulator, a pivoted plate C securing the end of the insulator, an oblique 25 slot b² in the second bracket, a spring D in the recess a¹ of the insulator, a plate d attached to the spring, stops b³ against which the plate rests, recessed arms E on the insulator, spring controlled contact pieces mounted 30 in the arms and fuse wires connecting the contact pieces and holding them against the force of their springs, substantially as herein described.

In witness whereof we have hereunto set 35 our hands in the presence of two witnesses.

ALBERT G. CHARTERS.
JOHN GRIFFITH JONES.
